UNITED STATES PATENT OFFICE.

CONRAD M. CONRADSON, OF GREEN BAY, WISCONSIN.

GYRATORY GRINDING MACHINE.

Application filed June 25, 1925. Serial No. 39,414.

This invention relates to gyratory grinding machines and more particularly to grinding machines in which the grinding element in the form of an abrasive disc is carried on a spindle designed to be driven at a relatively high speed, and the spindle in turn journalled in a rotative support which is driven at a slower speed about an axis offset from the axis of the spindle so as to produce a so-called gyratory motion.

The object of the present invention is to provide an electric driven grinding machine of the gyratory type in which the motor is incorporated in the machine, preferably with the rotor mounted directly upon the spindle, and the stator carried by the rotating spindle support.

A preferred embodiment of the machine is disclosed in the accompanying drawings, in which—

Figure 1 is a view in side elevation of the machine with a portion thereof shown in vertical section to show the internal construction thereof;

Figure 2 is a view in transverse vertical section taken on line 2—2 of Figure 1; and

Figure 3 illustrates diagrammatically the arrangement of the essential parts relative to the axis of gyration.

In Figure 1 is illustrated the head of an electric driven gyratory grinder of the horizontal spindle type, with the driving motor contained within the head and incorporated as integral parts of the spindle and spindle support.

The head consists primarily of a cylindric casing or housing 1, supported upon a pedestal 2, which rests upon the floor, said casing and pedestal being herein shown as integral with each other, with a wall 3 separating the two and forming the bottom wall of the casing. At each end of the casing are relatively large openings in axial alignment with each other, these openings being surrounded by inwardly extending annular flanges 4, within which are mounted annular bushings or collars 5—5, which support the end bearing assemblies for the rotative spindle support 6, which, as its name indicates, supports the spindle 7 through the medium of bearings mounted in bearing retainers which are offset from the axis of the spindle support. The ends of the spindle projecting from either end of the spindle support and carrying grinding discs 8—8, preferably consisting of circular metal plates to which

discs of abrasive material are applied to their outer faces.

Co-operating with each of the grinding discs are work tables, not shown herein, but well understood to be adjustable supports to which the work to be operated upon is fastened, the work tables being moved toward and from the face of the discs in the manner common to machines of this type. Before entering upon a more detailed description of the machine and its moving parts, it will be noted that the construction is the same at both ends of the machine, and parts formed at one end are duplicated at the other. This is particularly true of the bearing assemblies of spindle and spindle support.

Referring now to the construction of the spindle support 6, the same comprises two complementary end sections 9—9, supporting between them a central or intermediate section 10, the latter being in reality the stator of the motor and consists of a ring having a plurality of pole pieces 11 and coils 12 arranged about its internal circumference after the standard design of alternating current motors. The end sections 9—9 are generally conical in shape and correspond in general to the end frame members of a motor, with their base edges bolted to the ends of the stator ring 10, and their central portions forming the bearings for the armature or rotor shaft, which in this case is the spindle 7. Thus in Figure 2 each of the end sections is a hollow casting with a flaring wall portion 9^a converging from the stator ring 10 to an endwise extending hub portion 9^b, which is journalled in the bushing 5 by means of ball bearings 13, the usual type of ball bearing retainers and other standard features of bearing design being employed, which need not be described in detail. At this point it is important to observe that while the end bearing portions 9^b and their bearings determine the fixed axis of rotation of the spindle support, the stator ring 10, is eccentric to the end bearings, as is the periphery of the wall portions 9^a on either side of the stator. In other words, the spindle support is so designed that the stator rotates about an axis eccentric to its true axis, said axis, as will presently appear, being the axis of rotation of the spindle 7.

Referring now to the spindle 7 and its bearings, the same extends lengthwise of the spindle support and is journalled in bearings mounted in bearing cavities 16, formed

within the end bearing portions 9^b, these cavities, as shown in Figure 1, being eccentric to the spindle support bearings, as will be evident from comparing the distance between the set of roller bearings 13, and the set of ball bearings 17, which support the spindle within the bearing cavity 16. Here again the spindle bearing assemblies are designed in accordance with the standard practice and therefore need not be described in detail. Each of the grinding discs is fixed to the end of the spindle, preferably through the medium of a hub 18, keyed to the tapered end of the spindle.

15 Completing the spindle assembly is a rotor 23 fixed to the spindle intermediate its end bearings, its periphery being concentric with the axis of the spindle and also concentric with the stator frame 10 of the spindle support. The rotor is of the standard rotor design found in alternating current motors, this type of motor being preferably used, although other types may be equally well employed.

20 25 As will be presently disclosed, the spindle support, which includes the stator 10, rotates in its bearings, and therefore to supply current to the stator coils a collector ring is used for the purpose. As a preferred design 30 the collector ring 19 is mounted near one end of the spindle support by means of an annular flange 20, integral with one of the end sections 9 of the spindle support, this flange being concentric with the axis of rotation of 35 the spindle support. The collector is preferably of an insulating material with a plurality of peripheral contact rings 21.

Within the casing 1 and supported on the end flange 1^a thereof adjacent the collector 40 ring is a fixed brush holder 22 comprising brushes 23 engaging the contact rings 21. The brushes are connected with conductors 24 which lead to the source of current supply, whereas the contact rings are electrically connected with coils in the usual manner, thus the current is transmitted to the stator when in motion.

45 Referring now to the driving mechanism for the spindle support which, as clearly seen 50 from the foregoing description, is in reality the stator and end frames of an alternating current motor journalled in the casing 1 of the machine, there is formed integral with the stator frame 10 and extending completely around the central portion thereof 55 an integral worm wheel 25, said worm wheel being concentric with the axis of rotation of the spindle support, but eccentric to the stator frame which, as already pointed out, is concentric with the axis of the spindle 7. In other words, the stator and rotor must 60 necessarily be concentric with the spindle and therefore the stator is eccentric to the axis of rotation of the spindle support. To 65 compensate therefore for the eccentricity of

the stator the worm gear 29 is eccentric to the stator frame in an amount exactly equal to the eccentricity between the stator frame and the spindle 7. This relationship between the spindle, the stator and the worm wheel is clearly shown in the diagram of Figure 3.

70 Extending transversely of the casing 1 and beneath the stator is a shaft 26 journalled at one end in a bearing 27 supported in one side wall of said casing. The other end of the shaft has direct driving connection with a small auxiliary motor 28, bolted to the opposite wall of the casing. Mounted on the shaft 26 is a worm 29 which meshes 75 with the worm wheel 25.

80 Thus, assuming that the current is turned on to both the spindle driving motor and the spindle support driving motor, the spindle support at a relatively low speed, these two movements being imparted to the spindle simultaneously to produce the gyratory movement of the grinding discs 8, that is a combined rotation of the discs at a high 85 speed, and the bodily travel of the discs in a circular orbit about the axis of the spindle support. It follows therefore that during 90 this movement there is a relative rotation between the stator and the rotor, but, since 95 they both rotate about a common axis, and the speed of the stator is comparatively slow, the result is that the spindle is driven at the proper working speed.

If desired, it would be possible to drive 100 the spindle support, through the medium of gearing from the spindle, but inasmuch as such gearing would necessarily be complicated, it is considered to be much better practice to use a separate motor for driving the 105 spindle support.

I claim as my invention:

1. A grinding machine comprising a frame, a spindle support journalled in said frame for rotation about a fixed axis, a spindle journalled in said support and rotative about an axis eccentric to the axis thereof, an electric motor having a stator frame forming an integral part of said spindle support and disposed eccentrically to the axis thereof and concentric with said spindle and a rotor mounted on said spindle, and means for driving said spindle support independently of said spindle.

3. In a grinding machine, the combination of a housing, a spindle support journalled in said housing for rotation about a fixed axis, a spindle journalled in said spindle support for rotation about an axis eccentric to the axis of said support, grinding discs mounted at the ends of said spindle exterior of said housing, a motor mounted in said housing and comprising a stator mounted on 10 said spindle support concentric with said spindle, and a rotor mounted on said spindle.
4. In a grinding machine the combination of a frame, a spindle support journalled in said frame for rotation about a fixed axis, a spindle journalled in said support for rotation about an axis eccentric to the axis of said support, and means for driving said spindle and spindle support comprising a motor having its stator frame forming an 15 integral part of said support concentric with said spindle and its rotor mounted directly on said spindle, and an auxiliary motor having 20 driving connection with said support.
5. A grinding machine comprising a frame, a spindle support journalled in said frame, a spindle journalled eccentrically in said spindle support, means for imparting rotative movement in said support, and a motor for driving said spindle, comprising 25
- a rotor mounted on said spindle, a stator 30 incorporated in said spindle support and eccentric with respect to the axis of rotation thereof, a collector ring mounted concentrically on said spindle support, brushes mounted on said frame and engaging said 35 collector rings, and conductors leading to said brushes from a source of electric current and from said collector ring to said stator.
6. In a grinding machine the combination 40 of a frame housing a spindle support journalled at its ends in said housing, a spindle journalled eccentrically in said support and extending from opposite ends of said housing, grinding discs mounted at the ends of 45 said spindle and means for driving said spindle and spindle support comprising a motor having its stator forming an integral part of said spindle support and arranged eccentrically with said spindle, and its rotor 50 mounted on said spindle, and an auxiliary motor having driving connection with said spindle support through a gear member surrounding said stator frame and concentric with said support. 55
